RAILWAY TRUCK

Donald S. Barrows, Rochester, N. Y., assignor to
 The Symington-Gould Corporation, Rochester,
 N. Y., a corporation of Maryland

Application September 20, 1935, Serial No. 41,489

31 Claims. (Cl. 105—197)

This application is a continuation in part of my application Serial No. 402,203, filed October 24, 1929.

This invention relates to railway trucks and more particularly to the construction of the side frames, spring nests and spring plates thereof.

The principal object of my invention, generally considered, is the improvement in trucks and particularly the construction of the side frames, spring nests, spring plates and spring planks (if used), whereby increased strength of the frame and increased capacity of the bolster springs are secured, provision being made at the same time for the assembly and removal of nests of bolster springs with respect to the associated frames while said nests are assembled as units between associated plates.

Another object of my invention is to provide a railway truck of relatively short wheel base such as, for example, a wheel base in the neighborhood of five feet, using bolster spring groups of modified H shape to obtain increased spring capacity while avoiding interference between the springs and the associated brake rigging.

A further object of my invention is to provide a railway truck of reduced wheel base with the parts so constructed that interference between the inside hung brake beams and the inner spring support is avoided by decreasing the longitudinal dimension of the inner line of springs, this being accomplished by omitting a spring from said inner line and positioning it inwardly of said line preferably on the center line of the associated spring plank.

A still further object of my invention is the provision of a bolster particularly adapted for use with side frames of reduced wheel base and increased spring capacity.

An additional object of my invention is the construction of the side frames, spring planks and spring plates for use in a truck of reduced wheel base and increased bolster spring capacity.

Other objects and advantages of the invention relating to the particular arrangement and construction of the various parts will become apparent as the description proceeds.

Referring to the drawings illustrating my invention, the scope whereof is defined by the appended claims:

Figure 1 is a fragmentary side elevation of a truck embodying my invention, portions of the bolster and spring plank being shown in vertical section.

Figure 2 is a fragmentary horizontal sectional

view of the truck on the line 2—2 of Figure 1, looking in the direction of the arrows.

Figure 3 is a central transverse fragmentary sectional view of the truck shown in Figure 1.

Figure 4 is a horizontal sectional view on the line 4—4 of Figure 3, looking in the direction of the arrows.

Figure 5 is a fragmentary vertical sectional view on the line 5—5 of Figure 2, looking in the direction of the arrows.

Figures 6 to 12, inclusive, are diagrammatic views of spring arrangements alternative to that shown in Figure 2.

Referring to the drawings in detail, like parts being designated by like reference characters, and first considering the embodiment of my invention illustrated in Figures 1 to 5, inclusive, there is shown a portion of a railway truck comprising a side frame 1 preferably formed of cast steel, although it will be clear that some of the advantages of my invention may be obtained when using frames of other than cast construction. Said frame 1 comprises a compression member 2, a tension member 3, and bolster guide columns or strut portions 4 spacing intermediate portions of said compression and tension members leaving a window opening 5 therebetween. The compression and tension members extend outwardly beyond the bolster guide columns 4 where they join with one another and are either provided with integral journal boxes (not shown) or are adapted for connection with journal boxes, as will be understood by those skilled in the art. In the present embodiment of my invention the truck illustrated is one of a relatively short wheel base, so that the brake hanger brackets 6 are spaced very close to the guide columns and relatively close to one another, as illustrated particularly in Figure 1.

The tension member 3 between the bolster columns is generally box shape in cross section and comprises an upper web 7 forming a spring plank seat, a lower web 8 and side webs or flanges 9 and 10, respectively. For rigidifying and strengthening the side frame and particularly the tension member and the junction between the tension member and bolster guide columns, said tension member is upwardly convoluted or embossed preferably along the longitudinal center line of the frame adjacent the junctions with the bolster guide columns to form upper diagonally disposed web portions 11 which start near the center of the spring plank seat portion or upper web 7 and extend diagonally upward through the bolster guide columns toward the ends of the 55

frame. In the embodiment illustrated, the spring plank seat is of a size adapted to support a nest of springs of increased capacity, whereas the wheel base is abnormally short so that those portions of the tension member on either side of the guide columns extend upwardly and outwardly at a relatively steep slope. In order, therefore, to have the reinforcements 11 extend from near the center of the spring plank seat 10 to the guide columns without closing up too much of the window opening, said reinforcements preferably extend to the guide columns on a moderate inclination and after their union with said columns they are continued upwardly and outwardly 15 at a much steeper inclination, as indicated at 12 to correspond more closely with the relatively steep inclination of the main inclined end portions of the tension member. In this respect they differ from the construction of the side frame 20 described and claimed in my prior Patent No. 1,652,808 of December 13, 1927.

The reinforcing construction heretofore described results, in effect, in a bifurcation of the upper web of the tension member producing a 25 triangular or inclined reinforcement at the junctions between the tension member and bolster guide columns and in addition forms embossments with which the spring plank is adapted to engage, thereby obviating the necessity of the 30 usual squaring lugs or providing squaring means in addition to said lugs. The reinforcement also has the effect of reducing the effective depth of the window opening 5 for the insertion of the associated bolster 13, thereby making it desirable 35 to decrease the height of the front or outer guide lugs 14 to correspond with the distance between the bolster guiding portions 15 and the reinforcements 11. The rear or inner bolster guide lugs 16 may be of normal depth, if desired. 40 In order to provide an adequate spring-supporting area or spring plank seat, the upper web 7 between the bolster guide columns is laterally widened beyond the webs 9 and 10, as indicated at 17 and 18. These extensions 17 and 18 are 45 preferably braced with respect to the webs 9 and 10 by triangular gusset portions 19. The webs of the box-shaped portion of the tension member may likewise be braced, interiorly by gusset or 50 interior web portions 20, as shown most clearly in Figure 3.

In order to provide for a relatively great height or vertical dimension of the window opening 5, the compression member 2 thereover is preferably of decreased depth or has a web 21 with depending flanges 22 which are narrower or shallower 55 over the window opening than on either side thereof. In order, however, to provide for substantially uniform strength in the compression member, said flanges 22 preferably have beading 60 23 along the lower edges thereof, which beading is desirably of greatest size or width over the window opening or between the guide columns and tapers to decreased size or width on either side of the window opening, as indicated at 24, said beading 65 preferably sloping downwardly and outwardly to correspond with the lower edge of the compression member, as shown most clearly in Figure 1, and starting over the guide columns to diverge outwardly from the straight top edge of 70 said compression member.

In order to provide for secure connection of the associated spring plank 25 with the side frame 75 associated with each end thereof, as well as for positioning the spring units without the necessity of lower spring plates, the spring plank seat 1

of the tension member is preferably formed with a pair of upwardly extending bosses 26, preferably corresponding in diameter with the inner dimension of the spring units intended to be used, and being sufficiently longer than the thickness of the spring plank so that they extend thereabove and provide spring-positioning bosses, as shown most clearly in Figures 1, 2 and 3. If desired, certain of the bosses 27 may have the parts thereof, where they pass through the spring plank, of greater diameter than the spring-locating portions thereabove. If all of the spring units of the associated nest of springs 28 are double coil, as illustrated in Figures 1 and 2, the spring-positioning portions have diameters corresponding with the inner diameter of the inner coil, whereas if some of the spring units are single coil, as illustrated in some of the modifications to be hereinafter described, the spring-positioning portions may have a diameter corresponding with the inner diameter of the outer or single coil spring so that in this case the lugs 27 may be of uniform diameter larger than the lugs 26 which merely position the inner or small coils of the spring units. When using the larger spring-positioning bosses or lugs 27, whether or not they are used with single or double coil spring units, the diameter thereof where they pass through the spring plank 25 preferably corresponds with the inner diameter of the outer spring or a single 30 spring unit, so that in case such lugs are used with single coil springs or spring units, the diameter may be approximately uniform throughout the length.

The spring plank 25 is not only apertured to receive the bosses 26 or the bosses 26 and 27, but is upwardly embossed or corrugated, as indicated at 29, to nest over the corrugations or embossments 11 on the associated side frame. The inner boss 26, as well as the outer one, is desirably offset with respect to the longitudinal center line of the corrugations, as shown most clearly in Figure 2. The width of the spring plank at its outer end preferably corresponds with the width of the window opening and, in the present embodiment, is sufficient to receive three standard spring units disposed longitudinally of the associated side frame or transversely of the spring plank, outwardly of the embossments 29 and one standard spring unit directly between said embossments, or on the transverse center line of the frame or longitudinal center line of said plank and aligned with the central one of the three outer spring units, as illustrated particularly in Figure 2. In order, however, to avoid interference between the inside hung brake beams or rigging depending from the brake hangers, which, as previously explained, are abnormally close because of the short wheel base of the frame, the spring plank 25 tapers or decreases in width 60 from its ends beneath the window opening so that the row of spring units inwardly of the embossments 29 can only be two units long rather than three, as shown most clearly in Figure 2.

In order to maintain a spring capacity corresponding with the H shaped spring grouping described and claimed in my previous Patent No. 1,652,808, an additional spring unit 30 is preferably disposed inwardly of the two spring units which are inward of the corrugations 29, said additional spring unit being desirably positioned along the center line of the spring plank and forming with the adjacent spring units, a triangle, which in the present embodiment is substantially equilateral. It will be noted that this 75

additional spring unit is positioned so far inward, in order to provide normal clearance with respect to the adjacent springs, that it extends beyond the flange 18 of the tension member, making it impossible to position it by a lug or boss on the tension member. The positioning of this spring unit is preferably effected by means of a boss 31 on the spring plank, either formed integral with said plank or connected thereto in any desired manner as by means of a rivet 32. The spring units are preferably standard size and so positioned that the nest balances about the longitudinal center line of the frame. The spring plank, as is usual, preferably comprises a lower spring-supporting web 33 and flanges 34 on either side thereof. In order to press the plank from metal of uniform width, the flanges 34 are permitted to be of decreased depth at the ends of the plank, corresponding with the increased width thereof, as shown most clearly in Figure 3. In order to facilitate the assembly of the springs, and the application of shims, if necessary, spring plate 35 is preferably disposed above said springs, said spring plate being formed with spring-positioning collars 36 for engagement with all of the spring units and preferably conical spring plate locating bosses 37 adapted to fit in corresponding pockets 38 in the associated bolster 13. The bolster, of course, has a horizontally disposed necked portion 39 which preferably tapers in width to correspond generally with the tapering of the nest of springs and associated spring plank, said horizontal portion preferably being merely extended locally, as indicated at 40, to receive the innermost spring unit or corresponding portion of the spring plate 35, thereby providing a pocket 41 adjacent the longitudinal center line of the bolster and avoiding unduly increasing the length of the necked portion for the full width 40 of the bolster.

Referring now to the embodiments of my invention illustrated in Figures 6 to 12, inclusive, alternative spring groupings are there shown for capacities less than that of the previous embodiment. In the previous embodiment, for example, I provide for a seventy-ton capacity, while Figure 6 shows a corresponding arrangement for fifty-ton capacity. It will be noted that the spring arrangement in Figure 6 is substantially identical with that in Figure 2, except that the central spring unit or that between the reinforcements 11 of the frame is omitted and the two spring units immediately inward of said reinforcements are single coil rather than double coil. As in the previous embodiment, however, the springs are preferably so disposed that they balance about the longitudinal center line of the side frame.

Figure 7 shows an arrangement similar to Figure 6, but for forty-ton trucks, except that all of the spring units are single coil and the innermost unit is omitted rather than the central unit between the reinforcements 11.

Figure 8 shows an arrangement corresponding with Figure 6, except that the springs are arranged as two triangular groups, one inwardly and the other outwardly of the reinforcements 11, each group comprising two double-coil and one single-coil unit, the intermediate single-coil spring being offset or buckled inwardly in each instance. This arrangement is adapted for fifty-ton trucks.

Figure 9 shows an arrangement corresponding with Figure 7, except that four of the six spring units are double-coil rather than all being single-

coil adapting the arrangement for use with fifty-ton trucks.

Figure 10 shows a further modification adapted for forty-ton trucks using only five instead of six spring units, three of which are double-coil and two single-coil. The springs in this embodiment are arranged H shape in plan, but the uprights of the H are composed of two rather than three spring units.

Figure 11 shows a further modification using six spring units arranged in two triangular groups, the outer group comprising double-coil units and the inner single-coil units, both of said groups being arranged in approximately equilateral triangular formation. This arrangement is adapted for fifty-ton trucks.

Figure 12 shows a further modification corresponding with Figure 10 for forty-ton trucks using five spring units arranged H shape in plan with the outer upright of the H composed of double-coil spring units, the cross piece of the H composed of a double-coil spring unit and the inner upright of said H composed of single-coil spring units.

From the foregoing, it will be seen that I have devised an improved truck with a shortened wheel base while at the same time providing for increased spring capacity and avoiding interference between the inside hung brake beams or rigging and the spring plank and associated springs. Although preferred embodiments of my invention have been illustrated, it will be understood that I do not wish to be limited thereto as modifications may be made within the spirit and scope of my invention as defined by the appended claims. It will also be understood that although I have shown only one side frame and the associated ends of the bolster and spring plank, my truck, as is usual, is formed with two side frames, each of which supports an end of the spring plank and bolster.

I claim:

1. A side frame comprising a compression member, a tension member, struts interposed intermediate portions of said members and leaving a window opening therebetween, that portion of the tension member beneath the window opening forming a spring plank seat, said tension member outwardly of said seat comprising inclined end portions, each of which consists of upper and lower portions angularly disposed with respect to each other, the inclination of said upper portions changing at the struts so that they extend inwardly at a decreased inclination to merge with the spring plank seat adjacent the center thereof.

2. A side frame comprising a compression member, a tension member, struts interposed therebetween and spaced to leave a window opening, that portion of the tension member beneath the window opening being formed to support bolster springs, the tension member extending toward the ends of the frame from the spring-supporting portion thereof to form diagonally disposed end portions, each end portion comprising a plurality of sections, one of said sections starting from near the center of the spring-supporting portion, sloping upwardly and outwardly to the adjacent strut and from there sloping upwardly and outwardly at a materially increased inclination toward the adjacent end of the frame, and another section starting near the adjacent end of the spring-supporting portion and sloping toward the adjacent end of the frame.

3. A side frame comprising a compression mem-

- ber, a tension member, bolster guide columns interposed therebetween and spaced to leave a window opening, that portion of the tension member beneath the window opening being 5 adapted for supporting bolster springs, said tension member extending toward the ends of the frame from the spring-supporting portion thereof and consisting of an upper web portion, and another web portion disposed therebeneath, said 10 portions starting from different parts of the spring-supporting portion of the tension member and converging at their upper and outer ends, the inclination of said upper web portion sharply changing where it meets the bolster guide columns 15 15 so that the outer portions thereof have a steeper slope more nearly approximating that of the other portions.
4. A side frame comprising a compression member, a tension member, bolster guide columns 20 spacing intermediate portions of said members and spaced to leave a window opening, reinforcing members extending between the tension member and guide columns diagonally across the lower corners of the window opening being angularly 25 disposed from that portion of the tension member outwardly of said column members, that portion of the compression member above the window opening being relatively small in depth to provide for a relatively high window opening with 30 the portions outwardly thereof of a depth increasing from a straight top edge, the lower edges of said compression member being provided with beading, the depth of which is greatest over the window opening and decreases on either 35 side of said window opening to compensate for the variation in depth of the member and provide for approximately uniform strength thereof.
5. In a railway truck, in combination, a side frame formed with compression and tension 40 members spaced at intermediate portions thereof by bolster guide columns leaving a window opening therebetween, the tension member beneath the window opening being formed with a spring-seating portion, and a nest of springs supported on 45 said spring-seating portion, said nest being arranged with three units on a side omitting the units at the bolster columns and with the units on the inner side of said frame disposed in triangular formation.
- 50 6. In a railway truck, in combination, a side frame comprising compression and tension members spaced at intermediate portions thereof by bolster guide columns leaving a window opening therebetween, that portion of the tension member beneath the window opening being laterally 55 widened with the junction between it and the bolster guide columns reinforced by upwardly embossed portions extending along the longitudinal center line thereof from near the center through 60 the bolster guide columns toward the ends of the frame, a nest of springs supported on said portion, said springs being arranged in two groups lying on each side of the upwardly embossed portions, and a central spring disposed between said 65 groups and embossed portions, the group on the inner side of said embossed portions being arranged in triangular formation with an intermediate spring disposed inwardly with respect to the other springs.
- 70 7. In a railway truck, in combination, a side frame comprising a compression member, a tension member, bolster guide columns interposed therebetween and spaced to leave a window opening, that portion of the tension member beneath 75 the window opening being formed for supporting
- a nest of springs and reinforced with respect to the bolster guide columns by triangular upwardly extending embossments between the ends of said portion and the bolster guide columns, said embossments lying along the longitudinal center line of the frame, and a group of springs positioned on each side of said embossments, other springs disposed as a transverse group between said embossments, and an additional spring disposed inwardly of the group positioned on the inner sides of said 10 embossments.
8. In a railway truck, in combination, a side frame comprising a compression member, a tension member, bolster guide columns spacing intermediate portions of said members and leaving a 15 window opening therebetween, that portion of the tension member beneath the window opening being formed with embossments extending between the ends thereof and the bolster guide columns, a spring plank supported on said tension member 20 and formed with corrugations interlocking with the embossments, a nest of springs supported on said spring plank and arranged in modified H formation, the uprights of said H lying longitudinally of the frame on opposite sides of the corrugations of the spring plank, and the cross part of the H lying longitudinally of the spring plank between the embossments thereof, the inner upright of said H being of reduced height, thereby necessitating the positioning of an intermediate 25 spring thereof inwardly of the line of the other springs.
9. In a railway truck, in combination, a side frame comprising compression and tension members spaced at intermediate portions thereof by 30 bolster guide columns leaving a window opening therebetween, that portion of the tension member beneath the window opening being adapted to support a spring plank, a spring plank supported on said tension member, a nest of springs supported on said spring plank, said spring plank having the outer end thereof corresponding in width with the width of the window opening and decreased in width beneath said window opening, the nest of springs supported thereon being arranged with a greater number of springs in line 35 at the outer end of said plank than at portions inwardly thereof.
10. In a railway truck, in combination, a side frame comprising a compression member, a tension member, bolster guide columns interposed therebetween and spaced to leave a window opening, said frame being formed with brake hanger brackets disposed abnormally close together because of the frame having an abnormally short 40 wheel base, that portion of the tension member beneath the window opening being formed with a spring plank seat, a spring plank supported on said seat, and a nest of springs supported on said spring plank, said spring plank and the nest of 45 springs thereon being arranged to decrease in width from the end of the plank to avoid interference with associated brake rigging.
11. In a railway truck, in combination, a side frame comprising a compression member, a tension member, bolster guide columns interposed therebetween and spaced to leave a window opening, said frame having a short wheel base and provided with brake hanger brackets disposed 50 correspondingly close together, said tension member being formed with a spring plank seat, a spring plank supported on said seat, said plank being formed with its ends corresponding with the width of the window opening and tapered 55 inwardly to decreased width beneath the window 60

opening to avoid interference with associated brake rigging, and a nest of springs supported thereon.

12. In a railway truck, in combination, a side frame of short wheel base formed with a compression member, a tension member, bolster guide columns spacing intermediate portions of said members and leaving a window opening therebetween, the tension member beneath said window opening being adapted to support a spring plank, a spring plank supported on said seat portion and formed of maximum width at its ends and tapering inwardly to decreased width to avoid interference with associated brake rigging on account of the short wheel base of the frame, a nest of springs supported on said spring plank, said springs being arranged substantially H shape in plan with the uprights extending longitudinally of the frame on either side of the center line thereof, a central spring unit disposed between said uprights and forming the cross part of the H, an additional spring unit disposed inwardly of the inner upright of said H, and a bolster supported on said nest of springs, said bolster being formed with a horizontal surface directly above said springs and corresponding in area with the plan thereof, said horizontal surface being extended locally as a relief or channel in the bolster to accommodate the innermost spring without unduly increasing the length of the spring-supported portion thereof.

13. In a railway truck, in combination, a side frame comprising a compression member, a tension member, bolster guide columns interposed therebetween and spaced to leave a window opening, said frame beneath the window opening having a spring plank seat, a spring plank supported on said seat, said seat and plank being formed respectively with lugs and apertures receiving said lugs for locking said plank in place, said lugs extending above the level of the spring-supporting area of said plank and spaced to correspond with the spring arrangement desired, said plank being formed with a lug inwardly of said seat for positioning an inwardly disposed spring, and a nest of springs supported on said plank to correspond with the seat lugs and the additional spring plank lug.

14. In a railway truck, a side frame formed with a window opening, and a spring plank seat defining the lower portion of said opening, said seat having upstanding lugs, a spring plank resting on said seat and having apertures corresponding with said lugs for locking said plank in place, said plank having a lug connected thereto inwardly of the spring plank seat for positioning an additional spring, a nest of springs supported on said spring plank and positioned by said lugs, a spring plate supported on said nest of springs and formed with depending spring-positioning collars, a bolster resting on said spring plate, and means extending between said plate and bolster for holding the parts in proper position.

15. A nest of at least six bolster spring units formed as two rows with a central spring unit positioned directly between said rows making an arrangement substantially H shape in plan, and an additional spring unit disposed inwardly of the inner row of said arrangement.

16. A nest of at least seven bolster spring units for providing increased spring capacity and formed of maximum width outwardly and of decreased width inwardly of an associated side frame.

17. A nest of bolster springs comprising two

groups of at least three spring units each adapted for disposition, one group on each side of the longitudinal center line of an associated side frame, the inner one of said groups being arranged in inwardly decreasing triangular formation, and spaced from the other group with no overlapping of peripheral boundaries.

18. A spring plank formed of maximum width at its ends and tapering inwardly at the portions normally received in side frame bolster openings, whereby it is adapted to support a nest of springs which decreases in width toward the center of said plank.

19. A spring plate for a nest of springs formed generally H shape in outline and provided with at least six spring-positioning collars corresponding with the springs on the uprights and cross piece of said H, and an additional spring-positioning collar disposed laterally of one of the uprights of said H for permitting the employment of an additional spring unit to provide for increased spring capacity.

20. A nest of bolster springs comprising two groups each of at least three spring units, one group being arranged in triangular formation and disposed inwardly of the longitudinal center line of an associated side frame, and the other group being arranged in linear formation and disposed outwardly of, and with its periphery clearing, said longitudinal center line.

21. In combination, a bolster having its ends formed with lower horizontal surfaces adapted to be supported by resilient means, and spring plates disposed in engagement with said surfaces, said plates being widest at the outer ends and decreasing in width at the portions normally received in side frame bolster openings to inner still narrower portions adapted to engage single spring units.

22. A spring plank having ends flaring outwardly to maximum width, the flaring portions of said plank having upwardly extending transverse embossments adapted to receive corresponding portions on associated side frames for interlocking therewith.

23. In a railway truck, in combination, a side frame comprising a compression member, a tension member, bolster guide columns spacing intermediate portions of said members and spaced to leave a window opening therebetween, that portion of the tension member beneath the window opening being formed as a generally flat spring plank seat with embossments tapering from the lower end portions of the bolster guide columns to merge into the spring plank seat upper surface short of the central portion thereof, a spring plank with an end portion supported on said seat and formed with corrugations interlocking with said embossments, a nest of springs supported on said spring plank and comprising a plurality of springs disposed along the longitudinal center line of said plank, said plank having a pair of apertures lying on its center line beneath said springs and both offset from and being on the same side of the longitudinal center line of said corrugations, and said frame having lugs extending into said apertures to position said spring plank.

24. A spring plank comprising a supporting web and reinforcing flanges at the sides thereof, the ends of said plank being wider than intermediate portions thereof and the flanges being narrower at the widened end portions than between said end portions, said plank decreasing in width toward its center along the portions nor-

- 5 mally disposed adjacent the guide columns of as-
sociated side frames, and said web being pro-
vided with a plurality of apertures at each end
aligned along the longitudinal center line and
adapted to receive spring plank squaring lugs on
associated side frames.

6 25. A spring plank comprising a spring-sup-
porting web and flanges at the sides thereof, said
web tapering in width at an end portion and
having a plurality of spaced apertures in said end
tapered portion, adapted to receive lugs con-
nected to an associated frame, and disposed
along the transverse center line of said frame.

10 26. A spring plank having a bottom and side
flanges extending throughout the length thereof,
said plank tapering in width along portions nor-
mally disposed between the guide columns of as-
sociated side frames, so as to form, adjacent each
15 end thereof, portions wider than the balance of
the spring plank, said side flanges being of re-
duced height at the widened end portions of the
20 plank.

15 27. A spring plank having a web and flanges at
the sides thereof, said plank decreasing in width
25 toward its center along the portions normally
disposed adjacent the guide columns of asso-
ciated side frames, so that it is wider adjacent
the ends than intermediate the ends, said side
20 flanges being reduced in height at the widened
portions of the plank, and said plank at each
widened end portion having a plurality of aper-
tures extending longitudinally of said plank and
adapted to receive squaring lugs on associated
25 frames.

30 28. A spring plank comprising a supporting
web and reinforcing flanges at the sides thereof,
said plank being widest at the ends and decreasing
35 in width from the end portions toward inter-
mediate portions, along the portions normally
40 disposed between the guide columns of associated
side frames, said flanges being narrower at the
widened end portions than between said de-
creasing portions, and said web being provided ad-
45 jacent each end with a plurality of apertures
aligned along the longitudinal center line, dis-
posed toward the ends from said intermediate
portions, and adapted to receive spring plank
50 squaring lugs on associated side frames, at least
one aperture at each end being disposed in said
decreasing portions.

55 29. In a car truck, in combination, a side frame
formed with compression and tension members
spaced at intermediate portions thereof by col-
umns leaving a window opening therebetween,
said tension member beneath the window open-
55 ing having a spring plate supported thereby and
being formed with a spring-supporting portion,
relatively broad adjacent the outer side of the

frame and relatively narrow, for the support of
a single spring unit, adjacent the inner side of
said frame, and a nest of springs upheld by said
spring-supporting portion, said nest comprising
two rows of spring units extending longitudinally
of said frame and disposed on either side of the
longitudinal axis thereof, and a single spring
unit disposed inwardly of the inner row of
springs, over the narrow spring supporting por-
tion of said frame.

10 30. In a railway truck, in combination, a side
frame comprising compression and tension mem-
bers spaced at intermediate portions thereof by
struts and leaving a window opening therebe-
tween, that portion of the tension member be-
neath the window opening being formed to sup-
port bolster springs, the tension member beyond
the struts extending toward the ends of the
frame to form diagonally disposed end portions,
convoluted portions formed on said tension mem-
ber intermediate said struts and sloping upward-
ly and outwardly to the adjacent strut at an
angle of inclination different from that of the
tension member beyond said struts, said bolster
springs being arranged in two groups positioned
on each side of the convoluted portions, one of
said groups being arranged with three spring
units and the other of said groups being ar-
ranged in triangular formation, and a single
spring disposed on the longitudinal axis of said
side frame and between said convoluted portions.

15 31. In a railway truck, in combination, a side
frame comprising compression and tension mem-
bers spaced at intermediate portions thereof by
struts and leaving a window opening therebe-
tween, that portion of the tension member be-
neath said window opening being formed to sup-
port bolster springs, the tension member beyond
the struts extending upwardly and outwardly
toward the ends of the frame to form diagonally
40 disposed end portions, convoluted portions formed
on said tension member within said window
opening and sloping upwardly and outwardly
from adjacent the vertical center of the side
frame to the adjacent strut at an angle of in-
clination different from that of the diagonally
45 disposed end portions, said bolster springs,
formed as two rows with a central spring unit
positioned directly between the two rows, making
an arrangement substantially H-shaped in plan,
the rows of springs being positioned on each side
50 of the convoluted portions and the central spring
disposed between said convoluted portions and on
the vertical center of the side frame, one of said
rows having an additional spring associated
therewith to form a group of triangular for-
mation.

DONALD S. BARROWS.

DONALD S. BARROWS
